Primary Examiner—Melody N. Brown[57] **CLAIM**

The ornamental design for a rear mounted bike carrier, as shown and described.

DESCRIPTION

FIG. 1 is a front view of the rear mounted bike carrier showing my new design with the support arms in a collapsed position;

FIG. 2 is a left-side view thereof;

FIG. 3 is a left-side perspective view thereof with the support arms in an extended position and with one of the rear attachment bars shown broken away for convenience of illustration;

FIG. 4 is a top plan view of FIG. 1;

FIG. 5 is a left-side view of FIG. 3; and,

FIG. 6 is a top plan view of FIG. 3.
